CLAIM

The ornamental design for a door and windshield hangar for bearing promotional materials, as shown and described.

DESCRIPTION

FIG. 1 is a front view of a door and windshield hangar for bearing promotional materials.

FIG. 2 is a top view of a door and windshield hangar for bearing promotional materials.

FIG. 3 is a bottom view of a door and windshield hangar for bearing promotional materials.

FIG. 4 is a side view of a door and windshield hangar for bearing promotional materials.

FIG. 5 is an opposite side view of a door and windshield hangar for bearing promotional materials.

FIG. 6 is a close-up side view of region 6 of FIG. 5; and, FIG. 7 is a back view of a door and windshield hangar for bearing promotional materials.

In the drawings, the broken lines represent portions of the article that form no part of the claimed design.
